UNITED STATES PATENT OFFICE

ESMOND P. G. WRIGHT, OF CROYDON, JOHN H. E. BAKER, OF HAMPSTEAD, AND ALAN H. CAMERON, OF BRONDESURY, ENGLAND, ASSIGNEES TO WESTERN ELECTRIC COMPANY, INCORPORATED, OF NEW YORK, N. Y., A CORPORATION OF NEW YORK

TELEPHONE-EXCHANGE SYSTEM

Application filed May 10, 1928, Serial No. 276,734, and in Great Britain May 10, 1927.

This invention relates to telephone exchange systems and more particularly to systems of the character in which connections are extended between subscribers' lines by means of machine switching apparatus under the control of common register senders. The invention is especially adapted for use in large multi-office exchange areas and the object thereof is to provide a system of simple character which utilizes all apparatus involved to the most economical degree and with the greatest surety of operation.

In the prior art, systems employing power driven switches of the panel or rotary type controlled by common register senders, and systems employing switches of the Strowger or step-by-step type controlled by so-called "directors", have been disclosed for use in large multi-office exchange areas. The system of the present invention has been designed particularly to simplify the connection extending selectors and the equipment of the common register senders to order that less apparatus may be required for maintaining adequate service and in order that the cost of maintenance may be reduced as much as possible.

In the embodiment of the invention disclosed herein by way of illustration, all switches employed in the exchange are of the single motion rotary type movable in one direction only. The calling lines are associable with a first group selector by means of groups of link circuits each link circuit comprising a line finder and a selector finder. Each link circuit has access through its selector finder to a group of first selectors having access in turn to a single register sender. Associated with a group of link circuits is a distributor switch. Provision is made whereby, upon the initiation of a call in a group of calling lines, the distributor switch will select only an idle link, the selector finder of which has access to an idle first group selector in a group having access to an idle register sender. A single register sender is multiplied directly before all first group selector trunks of a selector group and may be associated with any one of the group selector trunks, no hunting for an idle sender being required other

than the hunting operation of the link distributor switch, whereby time is saved in associating an idle sender with a calling line and additional switches are obviated.

The selector switches of each switching stage except the first, are divided into groups and a minor or auxiliary switch is provided common to the selectors of each such group. The minor switches are directed by impulses transmitted thereto over the established connection from the common sender and mark the groups of terminals, and in the case of the final selector the desired line terminal to which their associated selectors shall hunt. The selector switches therefore have no directed movement but only a single hunting movement to find a terminal in the group marked by the minor switch. The first group selector is not provided with a minor switch but hunts to find an idle trunk in a group marked directly by the sender. Provision is also made that when a group selector hunts twice over its bank without finding an idle trunk in the group marked or the final selector hunts to the terminal of the marked wanted line and finds the line busy, all switches beyond the first group selector are released, the finder is dismissed, and a busy signal is transmitted from the first group selector to the calling line.

The minor switches may be made small and compact and therefore readily responsive to impulses transmitted thereto from the register sender. Further, since only one minor switch and the control relays therefor is required for a group of selectors, and the structure of the selector is extremely simple, only a rotary magnet and testing relay being necessary, an appreciable economy in equipment is realized. In addition since all selectors and minor switches are of the rotary single motion type, they may be mounted on hinged panels to either side of the mounting frame whereby they may be swung out to enable ready access to the cable connections extending thereto. By this arrangement an appreciable saving in mounting space is attained.

Connections between offices of the exchange area are extended over two-wire office trunks and provision is made at the outgoing ends of

such trunks to mark an entire group busy if the minor switch and control relays common to the incoming selectors in which the distant ends of the trunks terminate is unavailable. This busy condition is controlled over the two-wire trunks of the group without the additional use of extra conductors in the inter-office cable.

The common register-sender for controlling the setting of the minor switches is provided with a group of four registers which respond to impulses dialed by calling subscribers. The first two office code series of impulses are registered on two of these registers and are then transferred to translator switches. The third office code series of impulses is registered directly on one of the translator switches. Following the transfer of the code registrations to the translators the registers upon which they were initially registered are restored and are later employed, together with the two other registers, to register the numerical digits of the wanted line number. As soon as the office code has been completely registered the sender proceeds to transmit series of impulses for extending the connection from the calling line to the office in which the wanted line terminates. For this purpose a sending switch is employed which assumes a plurality of settings as directed successively from a plurality of banks of one or the other of the translators, terminals of the sending switch being multiplied to points in the banks of the translators with resistances interpolated between such contact points. The arrangement is such that when the sending switch has advanced to the point marked by a translator bank the direction of current flow through a relay will be reversed to mark the end of the selecting stage. Where the code registered on a translator indicates that the connection must be extended through more than three selecting stages to reach the desired office the translator is advanced one step following the completion of selections controlled through the three stages and in its advanced position controls selections through three additional stages.

In order that the apparatus of the exchange may at all times be maintained in proper condition for rendering efficient service a routine test circuit is provided for association with the common minor switches and control circuits serving groups of selectors at any switching stage. This test circuit may, at the option of an attendant, be rendered effective and will continue as long as desired to select idle minor switch control circuits and to test their operation, operating suitable alarm signals when any such circuit is found to function improperly.

Provision is also made for automatically hunting for any line of an office on which a calling condition exists for more than a predetermined period without the establishment

of a connection, such a condition arising through a permanent abnormal ground on the calling line or through the neglect of the calling subscriber to dial a number after initiating a call. When such a line is thus selected the number thereof is displayed on an indicator.

A clearer understanding of the invention will be obtained from a consideration of the following detailed description in connection with the drawings in which:

Fig. 1 shows a link circuit and preselecting arrangement;

Fig. 2 shows a portion of the first group selector;

Fig. 3 shows the remainder of the first group selector and a portion of the sender;

Figs. 4, 5, 6, 7 and 8 show the remainder of the sender;

Fig. 9 shows a second group selector;

Fig. 10 shows a testing arrangement for testing the control equipment of the group selector shown in Fig. 9;

Fig. 11 shows a relay arrangement for the outgoing end of a two-wire inter-office trunk;

Fig. 12 shows a selector at the incoming end of a two-wire trunk;

Fig. 13 shows a final selector;

Fig. 14 shows the common control equipment for the selector of Fig. 13;

Fig. 15 shows an arrangement for selecting and identifying a calling line on which a permanent signal condition exists;

Figs. 16 and 17 show a final selector and control equipment for connecting with private branch exchanges; and

Fig. 18 shows the manner in which the remaining figures should be arranged.

A brief summary of the operation of the system as a whole will first be given. The initiation of a call by a subscriber at substation 101 causes distributor switch 130 to hunt for a link circuit having access to a group of first group selectors served by a register sender which is idle. When such a link circuit, for example link 100, has been found the selector finder 120 is operated to find an idle selector in the group. The line finder 110 is then operated to connect the calling line to the selector and the distributor switch is advanced to the next link. When the calling line is connected through, the sender is associated therewith and with the selector by means of relay 203. There is such a relay for each first group selector and the sender is connected in multiple to the contacts of such relays in all of the selectors which it serves.

The called line designation is then recorded in the sender. The first digit of the office code is recorded on register 520 and transferred to translator 600. The second digit is recorded on register 510 and transferred to translator 650. The third digit is recorded directly on translator 600. Registers 520

and 510 are then restored to normal and the numerical digits are recorded on registers 540, 530, 520 and 510 in succession.

Immediately following the reception of the third digit the sending switch 850 is actuated. A distributing rack 810 is provided comprising a plurality of resistances 811 to 823 connected between battery and ground. The normal terminal of brush 854 of the sending switch is connected to ground and the succeeding terminals are connected to the distributing rack at points between succeeding resistances. The terminals of brushes 602, 603 and 604 of translator 600 and brushes 654, 653 and 652 of translator 650 are cross connected to distributing rack 810 in accordance with the routing corresponding to the setting of the translator. A circuit is established including brush 854 and translator brush 602, or 652 according to which translator is effective and switch 850 is advanced under the control of an interrupter until brush 854 reaches a terminal beyond that connected to the point marked by the translator setting so that the direction of current flow in the circuit is reversed. When this occurs relay 708 which is included in this circuit is operated, stopping the sending switch and preparing the circuit for the next selection. Due to the intimate relation between the sender and the first group selector the sending switch 850 is itself employed as the minor switch for that selector and the setting of the sending switch marks the group of terminals within which selector 300 is to hunt. Due to the large number of trunks outgoing from a first group selector, this selector is made up of two, or possibly more switch structures, with two operating magnets 301 and 302 and two test relays 209 and 210, while discrimination between the switches is made by the setting of the sending switch.

When the first group selector has been positioned, the sending switch becomes effective to control the sending out of impulses to the second group selector. Minor switch 910 is positioned in response to these impulses and marks a group of terminals over which the second group selector 900 hunts. Translator 600 provides for three selections while translator 650 provides for as many as six selections in order to pick a group of trunk outgoing to a desired office. Only two selectors have been shown, it being assumed that subsequent selectors would be essentially duplicates of the second group selector 900.

The first numerical digit controls the setting of minor switch 1210 whereupon switch 1200 is operated to select an intermediate selector which is not shown. This intermediate selector in turn picks a final selector. Two types of final selectors may be employed, that shown in Figs. 13 and 14 serving individual lines. The minor switch 1400 is positioned once for the tens digit after which the

final selector hunts for the group of ten lines marked by the minor switch. The minor switch is then restored and re-operated in response to the units digit and the final selector hunts for the called line so marked. The final selector shown in Figs. 16 and 17 will serve either individual lines or groups of trunks outgoing to private branch exchanges. For this purpose two minor switches are employed, a switch 1700 which is operated under the control of the tens digit and the switch 1710 which hunts for the group marked by the switch 1700 and is then itself positioned by the units digit on a terminal within the group. If the selected terminal corresponds to a private branch exchange the final selector first hunts for the terminal marked by the minor switch 1710 and then hunts for an idle branch exchange trunk. The final selector applies ringing current to the wanted line and completes the connection.

The operation of the circuits will now be discussed in more detail. Owing to the large number of contacts controlled by certain relays, these contacts will be referred to according to their numerical position counting from the relay out. For example, the innermost contact of relay 203 will be called the 1st front contact of that relay and the outermost contact will be called the 12th front contact. Only single motion rotary switches are employed as pointed out above. Three types of switches may be distinguished depending on the number of terminals to which each brush has access. For example, the selector switches and the translators have 100 sets of terminals each; the register switches and minor switches have 11 sets of terminals, while the sending switch constitutes a class by itself having 25 sets of terminals.

When the subscriber at substation 101 initiates a call by removing his receiver from the switchhook he completes a circuit from battery through the winding of line relay 102, outer left back contact of relay 103, over the substation circuit, back to ground at the inner left back contact of relay 103. Relay 102 in operating connects ground to conductor 125 for initiating the extension of the line to an idle first group selector. It also connects battery through the winding of relay 103, and in parallel therewith through resistance 132 and the right back contact of relay 103, to terminal 117 to identify the calling line to the line finder 110.

The connection of ground to conductor 125 completes a circuit over the outer right back contact of relay 122, conductor 133, winding of relay 104 to battery. Relay 104 in operating prepares a circuit from battery through the right winding of relay 105, right front contact of relay 104 to brush 106 to test the link circuits for availability. It also completes a circuit from battery through

the winding and back contact of magnet 107, left contact of relay 104, right back contact of relay 105, inner right back contact of relay 115 to grounded conductor 133. A link circuit having access to first group selectors associated with an idle sender is characterized by ground on the terminal to which brush 106 has access. If the link circuit on which switch 130 is standing is not ready for use, magnet 107 will operate in the above traced circuit to rotate distributor switch 130 until such a link circuit is found. At this time the circuit of relay 105 is completed, and may be traced from the terminal on which brush 106 stands, through resistance 108, back contact of relay 123, conductor 126, 4th back contact of relay 207, 1st back contact of relay 201, 2nd back contact of relay 205, conductor 213, middle contact of key 403, inner right back contact of relay 402, right back contact of relay 410, 1st left back contact of relay 400 to ground. Relay 105 operates opening the circuit of magnet 107, and bringing switch 130 to rest on link circuit 100. It also connects its low resistance left winding in parallel with its high resistance right winding to render the link circuit 100 busy to other distributor switches. The operation of relay 105 closes a circuit from battery, through the winding of relay 109, right front contact of relay 105, inner right back contact of relay 115, to grounded conductor 133. The operation of relay 109 closes a circuit for magnet 107 which holds the magnet operated until such time as relay 109 is released at the establishment of the connection. Magnet 111 is now operated in a circuit extending from battery, through the winding and back contact of magnet 111, brush 112, outer right back contact of relay 115, inner right back contact of relay 122 to ground at the inner right front contact of relay 109. The operation of magnet 111 causes the selector finder 120 to move in search of an idle first selector. Such a selector is characterized by battery on terminal 113 and when switch 120 reaches the terminals leading to such a selector, a circuit is completed from ground through the two windings of relay 115, left front contact of relay 109, brush 114 of distributor switch 130, brush 134 of selector finder 120, terminal 113, conductor 202, 2nd left back contact of relay 201, 3rd back contact of relay 207, 5th back contact of relay 205, conductor 214, right contact of key 403, left back contact of relay 402, left back contact of relay 410, right back contact of relay 400 to resistance 411 and battery. Relay 115 operates in this circuit, connecting ground to its low resistance winding in shunt of its high resistance winding, rendering the selector busy to other link circuits. The operation of relay 115 opens the circuit of magnet 111, bringing the switch 120 to rest. It also closes a circuit from

battery through the winding and back contact of magnet 116, over the terminal and brush 127 of switch 130, left back contact of relay 121, outer right front contact of relay 115, inner right back contact of relay 122 to ground at the inner right front contact of relay 109. Magnet 116 steps the line finder 110 in search of the calling line. As mentioned above, the calling line is characterized by battery on terminal 117. Therefore, when brush 118 engages terminal 117 a circuit is closed from battery over brush 118, terminal and brush 119 of the distributor switch, outer left front contact of relay 115, windings of relay 121 in series, to ground at the left back contact of relay 122. Relay 121 operates in this circuit connecting ground from the back contact of relay 122, through its low resistance winding alone, and over its right front contact directly to brush 119, shunting its high resistance winding. Relay 103 operates in series with this lower resistance, locking over its inner right contact to terminal 117 and relay 121. It releases line relay 102 and also opens the parallel circuit through resistance 132 to remove the calling condition from terminal 117. The operation of relay 121 closes a circuit from battery through the winding of relay 122, left front contact of relay 121, outer right front contact of relay 115, inner right back contact of relay 122 to ground at the inner right front contact of relay 109. Relay 122 operates and locks directly over its inner right front contact to the inner right front contact of relay 109. Relay 122 in operating connects ground over its left front contact to brush 124 and through the winding of relay 123 to brush 118 and the winding of relay 103. The operation of relay 123 connects the line finder brushes to the selector finder brushes and thus places the selector and sender under the control of the subscriber's substation. The operation of relay 122 releases relays 121, 104 and 109. Relay 104 in releasing releases relay 105 and relay 109 releases relay 115. Relay 109 also releases magnet 107 and steps the distributor brushes 130 to another link circuit, thereupon releasing relay 122. Relays 103 and 123 are held operated over the 1st front contact of relay 123, brush 134 of selector finder 120 and terminal 113, conductor 202 and thence to ground as previously traced. The operation of relay 123 completes a circuit from battery through the right winding of relay 200, over the ring conductor, through the link circuit, over the subscriber's substation loop, back over the tip conductor through the link circuit and to ground through the left winding of relay 200. Relay 200 in operating closes an obvious circuit for relay 201. Relay 201, in operating, connects ground directly to conductor 202, over a make-before-break contact to maintain the operation of relays 103 and 123. Relay 201

also closes a circuit from battery through the winding of relay 400, right back contact of relay 408, conductor 412, winding of relay 203, 3rd back contact of relay 209, 2nd back contact of relay 210, 1st back contact of relay 207 to ground at the 3rd front contact of relay 201. Relay 203 operates in this circuit and locks over its 1st front contact and the 1st back contact of relay 207 to the same front contact of relay 201. The operation of relay 203 places the first group selector under the control of the sender. It also completes a circuit from source of dial tone 204, over its 9th front contact, 4th back contact of relay 205, condenser 215 to the ring conductor for the purpose of informing the calling subscriber that the sender is ready to receive dial impulses.

Relay 400 in operating connects ground to conductor 401 for the purpose of starting interrupters 702 and 704, the operation of which will be described later. It closes a circuit from battery through the winding of relay 700, outer left back contact of relay 701, conductor 714, brush 503 of the register control switch in its normal position 1, conductors 547 and 413 to ground at the 2nd front contact of relay 400. Relay 400 also closes a circuit from battery through the right winding of relay 710, left back contact of relay 710, interrupter 702, right back contact of relay 710, conductors 711 and 413 to ground. Relay 710 closes its inner left front contact in response to the closure of this circuit.

When interrupter 702 opens, it operates fully through both windings and its inner left contact to ground over conductor 711. With relay 710 fully operated a circuit is closed from battery through the right winding of relay 703, 1st front contact of relay 700, right back contact of relay 703, interrupter 704, 1st left back contact of relay 703, brush 804 of the sender control switch 800 in its normal position 1 to ground at the middle left front contact of relay 710. Relay 703 closes its innermost left contact when interrupter 704 closes its contact and operates fully through both windings when the interrupter contact opens, at which time the circuit extends through the right winding of relay 703, 1st front contact of relay 700, left winding and 1st left contact of relay 703 and thence over brush 804 as traced above. With relay 703 operated a circuit is closed from battery through the winding and over the back contact of magnet 801, brush 802 in position 1, 3rd front contact of relay 703, outer right back contact of relay 402 to ground at the left contact of key 403. Magnet 801 steps switch 800 to position 2. The advance of switch 800 opens the holding circuit of relay 703 and that relay releases.

When the subscriber operates his dial he interrupts the circuit of relay 200 a number of times in the usual manner. At its first release relay 200 closes a circuit over its outer back contact, 1st front contact of relay 201, through the winding of relay 208 to battery. Relay 208 operates and because it is slow to release, remains operated throughout the dialing of each digit. A circuit is also closed from battery, through the winding of relay 205, inner front contact of relay 208 to ground at the 4th front contact of relay 201. Relay 205 locks over its right front contact, normal contact of relay 216, to ground at the 4th front contact of relay 201. A circuit is also closed at each release of relay 200 extending from battery through the winding of magnet 521 of register 520, normal contact of brush 502 of the register control switch 500, winding of relay 405, conductor 414, second front contact of relay 203, 1st front contact of relay 201 to ground at the outer back contact of relay 200. Therefore, register 520 is advanced in accordance with the first digit dialed by the subscriber. Relay 405 is operated in the circuit traced and closes a circuit from ground over its inner left front contact, winding of magnet 501 to battery, thus preparing a circuit for stepping the register control switch. At the completion of the first digit, relay 405 releases, magnet 501 also releases and switch 500 is stepped to position 2.

When switch 520 has taken two steps, a circuit is closed from ground over the normal contact of brush 506, brush 526 and its second contact, outer left front contact of relay 405, winding of magnet 531 to battery. Magnet 531 operates and releases when brush 526 steps off its second contact, thus advancing switch 530 to its first off-normal position. If switch 520 should be stepped only to its second terminal the release of relay 405 would also open the circuit of magnet 531, stepping switch 530. In position 2, switch 530 closes a circuit from battery through the winding and back contact of magnet 601, conductor 610, middle back contact of relay 406, 4th back contact of relay 404, off normal contacts of brush 536, 2nd and subsequent off normal contacts of brush 525, to ground. Magnet 601 steps switch 600 in search of the terminal marked by brush 526 due to the setting of register 520. When this terminal is found a circuit is completed for relay 406 extending over conductor 415 to brush 607 and the marked terminal cross-connected to a terminal to which brush 526 has access to ground over brush 506. The operation of relay 406 opens the circuit of magnet 601 and brings switch 600 to rest on the marked terminal.

Since switch 500 was advanced one step following the reception of the first digit, the closures of the back contact of relay 200 in response to the second digit causes the operation of magnet 511 and the advance of register 510 to a position corresponding to the second digit. As soon as switch 510 takes

125 130

one step off normal, a circuit is closed from battery through the winding of magnet 651 and its back contact over the inner back contact of relay 407, the 5th back contact of relay 404, off normal contacts of brush 515, contacts of brush 505 to ground over conductor 547. Switch 650 is therefore set in motion to find the terminal marked by switch 510. When this occurs a circuit is completed from battery through the winding of relay 407, 6th back contact of relay 404, conductor 430, brush 656 and the marked terminal cross-connected to the terminal of brush 516, brush 505 to ground over conductor 547. The operation of relay 407 brings switch 650 to rest.

The release of relay 405 at the end of the second digit steps switch 500 to position 3. In this position the release of relay 200 controls magnet 601 directly. The circuit for this purpose may be traced from battery through the winding of magnet 601, brush 502 in position 3, winding of relay 405, and thence as previously traced to ground at the back contact of relay 200. The third series of impulses therefore sets switch 600 on a terminal which is jointly determined by the first and third series of impulses.

At the conclusion of the third digit a circuit is closed from battery through the winding of magnet 531 and its back contact, brush 535 and its multiplied contacts, brush 505 in position 4, to ground over conductor 547. Switch 530 is therefore restored to normal for the reception of a subsequent digit. From an inspection of Fig. 5 it will be apparent that the numerical designation of the wanted line made up by the next four series of impulses will be registered on registers 540, 530, 520 and 510, respectively, switch 500 being advanced from position to position in the previously described manner following the reception of each digit.

Since registers 520 and 510 have already been used to record the first two digits and this record has been transferred to the translator switches 600 and 650, these two registers are restored with switch 500 in positions 5 and 6, respectively, and are therefore ready for use at the time the digits to be registered thereon are received. The circuit for restoring switch 520 extends through the winding of magnet 521 and its back contact, brush 524 and its off normal terminals, inner right back contact of relay 405, brush 505 in position 5, to grounded conductor 547. The circuit for restoring switch 510 extends through the winding of magnet 511 and its back contact, brush 514 and its multiple contacts, brush 505 in position 6 to grounded conductor 547.

In the meantime as soon as the third digit was received, control of selections started. The code digits representing the directory number of the wanted office are translated by switches 600 and 650 into registrations

which control the selection of the desired exchange. Either switch 600 or switch 650 may be employed. Translator 600 controls selections which take place in the usual manner involving three selective operations. Translator 650 is capable of controlling as many as six selective operations in extending a connection to the distant office. When the office code dialed represents a routing controlled by switch 600, the terminal to which brush 607 has access is cross-connected to a terminal in the group to which brush 656 of translator 650 has access after being set. If, however, the code indicates that translator 650 is to control, the terminal on which brush 606 is to be set is cross-connected to a point on the terminal bank of brush 656. The corresponding terminals of brushes 602, 603 and 604 or of 652, 653 and 654 are then connected to distributing rack 810 to control the selection of the wanted office. When switch 500 moves into position 4, relays 406 and 407 release and relay 404 operates over the back contacts of relays 406 and 407, fourth and subsequent terminals of brush 506 to ground. Relay 404 locks over its innermost front contact to grounded conductor 547. With relay 404 operated a circuit is completed from battery through the winding and back contact of magnet 651, inner back contact of relay 407, 7th front contact of relay 404, conductor 432, contacts engaged by brush 655 to ground. Assuming that translator 600 is to be used, when brush 656 engages the terminal cross-connected to the terminal on which brush 607 has been positioned, a circuit is closed from battery, through the winding of relay 406, conductor 415, brush 607, cross-connecting conductor, brush 656, conductor 430, 9th front contact of relay 404, normal contact of relay 406, 8th front contact of relay 404, 4th and subsequent contacts of brush 507 to ground at the 3rd front contact of relay 400. Relay 406 locks over the 8th front contact of relay 404 and thence as traced to ground. Switch 650 continues to advance until brush 655 encounters a normal terminal such as 657 at which time the circuit for switch 650 is opened and a circuit is closed from ground, over brush 655, terminal 657, 3rd front contact of relay 404, conductor 416, 3rd back contact of relay 707, brush 804 in position 2, 1st back contact of relay 703, interrupter 704, right back contact of relay 703, 1st front contact of relay 700, right winding of relay 703 to battery. As before relay 703 energizes partly when interrupter 704 closes and then completely when it opens.

If a call is dialed indicating that translator 650 is to be used, magnet 651 is operated following the operation of relay 404 as above described. As stated above, for such a code combination the terminal engaged by brush 606 will be cross-connected to a terminal in the group on which brush 656 has been set

instead of a terminal engaged by brush 607. Therefore when brush 656 encounters this terminal relay 406 is not operated, but relay 407 is operated in a circuit which may be traced from battery, through the winding of that relay, 10th front contact of relay 404, conductor 431, brush 606 cross-connected to terminals to which brush 656 has access, conductor 430, 9th front contact of relay 404, 10th normal contact of relay 406, 8th front contact of relay 404, multiplied contacts of brush 507, third front contact of 400 to ground. Relay 407 in operating opens the circuit of magnet 651 and brings translator 650 to rest 15 on the marked terminal. Relay 407 locks in a circuit extending from the 10th front contact of relay 404, outer front contact of relay 407, 7th front contact of relay 404, conductor 432, terminal of brush 655 to ground. 20 With relay 407 operated a circuit is closed from battery, through the winding and back contact of magnet 601, conductor 610, middle back contact of relay 406, 6th front contact of relay 404, inner front contact of relay 25 407, strapped terminals and brush 605 to ground. Switch 600 is enabled to pass terminals such as terminal 611 since the operation of relay 404 connects the strapped terminals over conductor 613 and the 12th front contact of relay 404 to conductor 612 and the unstrapped terminal 611 to grounded brush 605. When the normal terminal 614 is reached, the circuit for operating relay 703 is closed over brush 605 instead of brush 655 35 and selections may proceed under the control of translator 650.

The operation of relay 703 as above described initiates the first selecting operation. Sending switch 850 and translator 600 cooperate to control selecting operations through the distributing frame 810. Frame 810 comprises resistances 811 to 823 inclusive arranged in series and connected to ground and battery. The translator terminals are cross-connected between the resistances in accordance with the selections to be made, while successive terminals of brush 854 of the sending switch are connected to the successive resistances. Since the selection control circuit is connected between the translator brush and brush 854, we have in effect a potentiometer with the translator brush the fixed terminal and brush 854 the movable terminal.

When relay 404 operated a circuit was closed from battery, resistance 705, 2nd left back contact of relay 703, winding of relay 706, 4th back contact of relay 707, 11th front contact of relay 404, brush 854 in its normal position to ground. Relay 706 operates in this circuit. When relay 703 operated, the circuit of relay 706 was altered so that it extended from ground through the winding of relay 706 as above traced and thence over the 4th left front contact of relay 703, front con-

tact of relay 706, lower winding of relay 708, brush 805 in position 2, brush 602 and the terminal upon which it is standing which it will be assumed is cross-connected to the distributing frame 810 at a point between resistances 821 and 822 so that the circuit is completed through resistances 822 and 823 to battery.

With relay 703 operated the next closure of interrupter 704 completes a circuit from battery through the winding of magnet 851 of the sending switch, right front contact of relay 703, interrupter 704, 2nd left front contact of relay 703, to ground over conductor 416 as previously traced. At each closure of interrupter 704, magnet 851 operates and advances switch 850 one step. When switch 850 takes its first step the resistance 811 is included in the circuit of relays 706 and 708. Relay 706 is slow to release and does not open its circuit while switch 850 is stepping from terminal to terminal. After switch 850 has taken a second step, resistances 811 and 812 are both included in the circuit of relay 706 and similarly resistances are added after each step of switch 850. When brush 854 reaches its 12th terminal there is no drop in potential across the winding of relay 706 and that relay releases.

When relay 706 releases the circuit through the lower winding of relay 708 extends from brush 854 to the 4th back contact of relay 707 as above traced, over the 5th front contact of relay 703, the back contact of relay 706, and thence through the lower winding of relay 708 to brush 604 as before. When brush 854 reaches its 13th terminal brush 854 is connected to a point on frame 810 nearer battery than the point to which brush 602 is connected and therefore the direction of current flow through the winding of relay 708 is reversed. This relay is electrically polarized by a circuit through its upper winding extending from battery through that winding to ground over conductor 711. The current in this winding tends to close the upper contact of the relay but is just insufficient to do so alone. The current flowing in the opposite direction through the lower winding holds the armature in the position shown. When brush 854 engages its 13th terminal the current flowing in the lower winding aids the current in the polarizing winding and relay 708 operates to close its upper contact. With relay 708 operated an obvious circuit is closed for relay 701. Relay 701 opens the circuit of relay 700; relay 700 in turn opens the holding circuit of relay 703; and relay 703 releases relay 708. Relay 701 is held operated over the lower contact of relay 708, 1st back contact of relay 709, 2nd left front contact of relay 701, brush 803 in position 2, 4th front contact of relay 404 to ground. The release of relay 703 brings switch 850 to rest on its 13th off normal terminal.

The group of contacts to be selected by the first group selector is marked directly by the sending switch. This is possible because of the intimate relation between the sender and the first group selector which are located at the same office. The operation of relay 701 closes a circuit for the stepping magnet of the first group selector. It will be remembered that the first group selector may comprise two physical switches. Selector 300 is such a selector, brushes 303, 305, 307 and 309 forming a part of one switch operated by magnet 301 and brushes 304, 306, 308 and 310 of a switch operated by magnet 302.

15 Which switch is to be employed is determined by the setting of the sending switch. Since brush 857 is on terminal 13, magnet 301 is operated. The circuit of magnet 301 may be traced from battery through its winding and back contact, 3rd back contact of relay 210, 10th front contact of relay 203, 13th terminal of brush 857, 2nd front contact of relay 701, brush 803 in position 2, 4th front contact of relay 404 to ground. Magnet 301 moves its corresponding set of brushes in search of an idle trunk in the group marked by brush 856. An idle trunk is marked by low resistance battery connected to a terminal to which brush 307 or 308 has access. Since 30 brush 307 is individual to the switch operated by magnet 301 if that brush encounters a terminal to which low resistance battery is connected at the same time that brush 309 engages a contact of the marked group 311, a 35 circuit will be completed from battery on such terminal, brush 307, 1st back contact and right winding of relay 210, 6th front contact of relay 203, brush 309 and one of the multipled terminals of group 311, 13th terminal 40 of brush 856, to ground at the 3rd left contact of relay 701. Relay 210 operates in this circuit and connects ground from the 5th front contact of relay 201, over the 2nd back contact of relay 207, 1st front contact of relay 45 210, to the terminal engaged by brush 307, and also closes a holding circuit for itself from battery, through the winding of magnet 301 and its back contact, over the 3rd front contact and the left-hand high resistance 50 winding of relay 210 to ground at the front contact of relay 201. The operation of relay 210 extends the control circuits from the sender to the second group selector shown in Fig. 9.

55 At the second group selector shown in Fig. 9, the apparatus above the dotted line is individual to the selector while that below is common to the group of selectors. The low resistance battery by which the selector was 60 identified as idle was supplied through resistance 932, brush 912 of the minor switch 910 which normally stands in the position shown, middle back contact of relay 924, 2nd back contact of relay 922, and a parallel there- 65 with through the winding of relay 922, thence

through the winding of relay 920, 1st back contact of relay 927 to conductor 938 and the terminal of brush 307. When relay 210 operated, relays 920 and 922 operated in the circuits traced. With relay 920 operated a circuit is closed from ground, the outer back contact of relay 921, 4th front contact of relay 920, over the tip conductor to terminal 321, brush 303, 3rd front contact of relay 210, 3rd front contact of relay 203, conductor 720, right front contact of relay 701 to battery through the winding of relay 712, operating relay 712. The operation of relay 922 closes a circuit from battery, through the winding of relay 923, inner back contact of relay 924 to ground at the right contact of relay 922. Relay 923 in turn closes a circuit for relay 925 to ground at the inner back contact of relay 926. Relay 924 then operates in a circuit over the 1st front contact of relay 922, outer front contact of relay 923, outer front contact of relay 925, normal contact of brush 915 to ground. With relay 924 operated the circuit of relay 923 is transferred over the inner front contact of relay 924, inner front contact of relay 925, outer back contact of relay 926, 5th contact of relay 920 to the ring conductor and thence over terminal 313, brush 305, 5th front contact of relay 210, 8th front contact of relay 203, conductor 721, right front contact of relay 710, inner front contact of relay 701, left winding of relay 713 to ground.

When relay 210 operated it closed a circuit from ground, over its right front contact, 5th front contact of relay 203, off normal contacts of brush 852, winding of relay 709 to battery. Relay 709 operates opening the holding circuit of relay 701. Relay 701 being slow to release retracts its armatures only after an interval. When 701 finally releases it closes a circuit for relay 700 over the outer back contact of relay 701 and the front contacts of relays 712 and 713. Relay 700 operates, closing a holding circuit for relay 712. In the meantime a circuit has been closed from battery, through the winding of stepping magnet 851 and its back contact, 3rd back contact of relay 703, brush 852 and its off normal terminals and thence as previously traced to ground at the front contact of relay 210. Switch 850 is advanced to position 14 which is a normal position and in which position the circuits of relay 709 and magnet 851 are opened. When relay 709 operated it closed a circuit from battery, through the winding of magnet 801, 3rd front contact of relay 709, to ground at the 3rd front contact of relay 400. When relay 709 now releases it opens this circuit advancing the sender control switch to position 3 and preparing for the next selection.

Since the selectors have no normal positions, special means is provided to inform the calling subscriber when all outgoing

trunks are busy. Assuming that all of the trunks of the marked group are busy switch 300 will not be brought to rest by the finding of an idle trunk and will continue to hunt. The first time that brush 307 passes over terminal 315 a circuit will be closed from grounded terminal 326, brush 309, 6th front contact of relay 203 through the winding of relay 210 as previously traced back to brush 307, terminal 315, strapped terminals of brush 858, conductor 316, back contact and right winding of relay 722 to battery. Relay 722 closes its inner front contact and when brush 307 leaves terminal 315 closes its remaining contacts and locks through its two windings in series, middle front contact of relay 701, brush 803 in position 2, 4th front contact of relay 404 to ground. Relay 210 does not operate in the above traced circuit. When brush 307 again engages terminal 315 (thus insuring that every outgoing trunk has been tested) the circuit traced for relay 722 is extended over the middle front contact of relay 722 to the right winding of relay 713 and in parallel therewith to the winding of relay 408. Relay 210 operates in this circuit bringing the switch to rest on a set of blank terminals. Relay 408 operates and locks over its inner front contact to the 2nd front contact of relay 400 releasing relays 400 and 203 and causing the restoration of the registers. Relay 713 which also operated closes a circuit from ground, over its front contact, back contact of relay 712, 4th front contact of relay 203, left winding of relay 220 to battery. Relay 220 extends its operating ground over its inner left front contact to the winding of relay 207. Relay 207 releases relay 210 and provides a circuit extending from busy tone connected to conductor 230, 4th front contact of relay 207, 4th front contact of relay 205, condenser 215 to the ring conductor, providing a busy tone signal to the calling subscriber. The restoration of the receiver at the calling station releases relay 201 and removes the locking grounds from all relays.

The sending switch is arranged so that selector 300 will continue hunting for an idle trunk to an operator's position even though none be idle when the group is first tested. For this purpose those terminals of brush 858 corresponding to groups of operator's trunks are not connected to terminal 315 and hunting is not arrested in the manner above described. With relay 709 released the tip conductor 720 extends in the sender over the right back contact of relays 701 and 709 to ground at the 2nd contact of relay 700, while the ring conductor 721 extends to relay 713 over the 3rd back contact of relay 709 in place of the inner front contact of relay 701.

When relay 700 reoperates it prepares the circuit of relay 703 which operates under the control of interrupter 704 as previously de-

scribed. It also closes the circuit previously traced for operating magnet 851 under the control of interrupter 704. When brush 852 engages its 15th terminal relay 709 is reoperated from the front contact of relay 210. With relay 709 reoperated, the tip conductor 720 is extended over the right normal contact of relay 701, the right front contact of relay 709, outer left front contact of relay 710 to contact of interrupter 702. The ring conductor 721 extends directly to the opposite contact of interrupter 702. Interrupters 702 and 704 operate simultaneously so that for each step of switch 850 under the control of interrupter 704 the tip and ring conductors will be disconnected momentarily at interrupter 702.

Therefore, at each step of switch 850 relay 923 will release closing a circuit from battery, through the winding of stepping magnet 911 of the minor switch 910, right back contact of relay 923, outer front contact of relay 924, 3rd front contact of relay 922 to ground. The circuit of relay 924 is opened as soon as brush 915 moves off normal, but it is held operated during pulsing over a circuit including the 1st front contact of relay 922, left back contact of relay 923, outer front contact of relay 924, 3rd front contact of relay 922 to ground. The circuit for determining the number of impulses to be sent out is similar to that previously traced, differing in that it extends over brush 805 in position 3 and over translator brush 603 to a point on potentiometer 810. When sufficient pulses have been sent out relay 708 is operated as before, in turn operating relay 701 and extending the tip conductor 720 to battery through relay 712 and the ring conductor 721 to ground through relay 713, thus rendering the circuit independent of interrupter 702.

When this occurs, the circuit of relay 924 remains open long enough to permit that relay to release, closing a circuit for magnet 901 of the main switch 900, over its back contact, 2nd back contact of relay 927, 2nd front contact of relay 920, middle back contact of relay 926, outer back contact of relay 924, off normal terminals and brush 915 to ground. Magnet 901 advances switch 900 in search of an idle trunk in the group marked by switch 910. Assuming that the group 939 is the one marked, switch 900 will be advanced until brush 903 encounters low resistance battery within the marked group whereupon a circuit is completed from such battery, brush 903, right winding of relay 927, 3rd contact of relay 920, brush 902, to a terminal in marked group 939, brush 912, middle back contact of relay 924, 3rd front contact of relay 922 to ground. Relay 927 closes a holding circuit for itself through the winding and back contact of magnet 901, 2nd front contact of relay 927, left winding, and 1st front contact of

relay 927, conductor 938 to ground at the front contact of relay 201 as previously traced. The operation of relay 927 opens the circuit of relay 920, which in turn releases 5 relays 922, 923 and 925. The release of relay 923 closes a circuit from battery through the winding of magnet 911, right and left back contacts of relay 923, 1st back contact of relay 922, back contact of magnet 911, off normal terminals of brush 915 to ground. Minor switch 910 is restored to normal in this circuit 10 and thus restores the common equipment for use in connection with other group selectors.

The second group selector is also arranged 15 to release if no idle outgoing trunks exist. The first time that brush 902 encounters terminal 929 a circuit is closed from ground over terminal 929, brush 902, 3rd contact of relay 920, right winding of relay 927, brush 903, 20 terminal 930, 1st contact of relay 920, off normal terminals of brush 913, 4th front contact of relay 922, inner back contact and winding of relay 921 to battery. Relay 921 closes its inner front contact and when brush 902 leaves 25 terminal 929, closes its remaining front contacts and locks in a circuit through its windings in series and outer front contact to ground at the right front contact of relay 922. On the second engagement of terminal 929 30 the circuit of relay 921 is extended over the inner front contact of relay 921 to the winding of relay 926 and battery. Relay 921 removes ground from the tip conductor and relay 926 connects battery through resistance 35 932, outer front contact of relay 926, 5th contact of relay 920 to the ring conductor thus operating relay 713 alone and giving the subscriber a busy tone in the manner described for the first group selection. The release of 40 relay 210 as described in that connection removes ground from conductor 938 and releases the second group selector. If the second group selector has access to any groups of operators' positions the terminal of brush 913 45 corresponding to such group is not connected to the others and the switch is permitted to hunt until a trunk is found.

In the course of an ordinary call three 50 selective operations occur within the calling office, i. e. a third group selector is interposed between Fig. 9 and Fig. 11. Since this selector would be substantially a duplicate of the second group selector it has been omitted to simplify the drawing.

55 When the call extends to a distant exchange a relay arrangement such as shown in Fig. 11 is used in connection with the interoffice trunk so that the trunk may contain only two wires. When the third group selector seizes 60 the outgoing trunk and ground from the test relay is connected to the terminal to which conductor 1107 is connected, the circuit extends over the outer right back contact of relay 1100, winding of relay 1101, left winding of relay 1102 and in parallel therewith

over the back contact of relay 1102, resistance 1105 to battery.

Relays 1102 and 1101 operate in this circuit and close a circuit from ground over their front contacts to the winding of relay 1100. Relay 1100 locks over its right front contact, conductor 1107, a terminal of the third group selector similar to 928, over the inner front contact of a relay similar to 927 to terminal 928, inner front contact of relay 927, conductor 938 and ground. Relay 1102 is common to all the trunks of the group and while operated disconnects battery through resistance 1105 from conductor 1107 to mark the group busy. Relay 1100 in operating completes the ring conductor from the calling office to the called office and disconnects relays 1101 and 1102 from the release conductor. It also closes a circuit for relay 1103 which operates and holds certain circuits in readiness 85 for subsequent use.

The incoming selector at the distant office, shown in Fig. 12 is controlled by means of equipment common to a group of such selectors in much the same manner as the selector of Fig. 9, the common equipment being shown below the dotted line. With the tip and ring conductors extended to the selector of Fig. 12, a circuit may be traced from ground, over the outer upper back contact of relay 1229, 6th back contact of relay 1225, upper winding of relay 1226 to the tip conductor and thence to the winding of relay 712 and battery. A circuit may also be traced from battery, through resistance 1220, back contacts of relays 1221, 1222 and 1223, right winding and back contact of relay 1224, 5th back contact of relay 1225, lower winding of relay 1226, to the ring conductor and thence to the winding of relay 713 and ground. The operation of these two 100 relays initiates the sending out of the next series of impulses in the manner previously described.

Returning to the sender, at the end of the second group selection relay 701 is operated 110 as above described. The holding circuit previously traced does not exist since the sender control switch has left position 2, but relay 701 being slow to release prevents the sending of additional pulses and holds the selector while 115 it is hunting for an outgoing trunk. Relay 700 and relay 703 are released in turn and the release of relay 703 advances the sending switch to its normal position where relay 709 releases. With both relays 701 and 709 released the tip and ring conductors are extended to the windings of relays 712 and 713 respectively and these relays operate when the tip and ring are connected through to the third group selector. At the end of the third group selection in the case assumed, i. e. that translator 600 is in use, a circuit is closed from battery through resistance 728, right winding of relay 707, inner back contact of relay 701, brush 803 in position 5 to ground at 130

the fourth front contact of relay 404. Relay 707 locks through its left winding and 1st front contact to grounded conductor 711. Relay 707 opens the circuit of relay 706 and 5 the previously used circuit for operating relay 703. It also closes a circuit from battery, through the winding and back contact of magnet 801, brush 802 in positions 3 to 7, second front contact of relay 707, 4th back contact of 10 relay 709 to ground at the third front contact of relay 400, thus advancing switch 800 over the positions in which further selections might be made under the control of translator 650.

15 With switch 800 in position 4 stepping magnet 651 of translator 650 is energized in a circuit extending over the right back contact of relay 707, brush 803 in position 4 to ground at the 4th front contact of relay 404. When 20 switch 800 is advanced to position 5 this circuit is opened and translator 650 is advanced one step. If this translator was standing at normal the advance has no effect. If it, however, is standing in a position from which it is 25 to control more than three selections the terminal engaged by brush 656 in its advanced position is connected to resistance 723 in shunt of the winding of the relay 707 and selections are permitted to continue in the manner described.

30 For the purpose of controlling the numerical selections relay 703 is energized in a circuit which extends as previously traced to brush 804 and thence in positions 8 and 9 to the off normal terminals of brush 534 on register 530 and in positions 10 and 11, over terminals of brush 505 of the register control switch to grounded conductor 547. The sending switch is advanced under the control of interrupter 702 until brush 855 engages the 35 terminal marked by one of the registers. In the case of the first numerical selection, for example, when the marked terminal is encountered a circuit is closed from battery, through the winding of relay 701, upper contact of relay 708, first front contact of relay 709, brush 855 and its marked terminal, terminal of brush 543, brush 803 in position 8 to ground at the fourth front contact of relay 404. The effect of relay 701 is the same as for 40 selections controlled by the translator.

45 When relay 1224 operates in the circuit previously traced it closes a holding circuit for itself from battery, through its left winding and 4th front contact to ground at the upper contact of relay 1226. With relay 1224 operated a circuit is closed from ground at its 50 1st front contact, 2nd back contact of relay 1225, winding of relay 1223 to battery.

55 60 Relay 1223 in operating connects ground over its middle front contact to the back contact of relay 1224. Relay 1224 being operated this ground is ineffective. Relay 1223 is common to all selectors of the group and in those 65 selectors which are idle the relay correspond-

ing to relay 1224 is not operated. Therefore circuits will be closed similar to one which may be traced over the back contact of relay 1224, 5th back contact of relay 1225, through the lower winding of relay 1226, to the ring 70 conductor of the interoffice trunk, over the outer left back contact of relay 1100, back contact of relay 1103, to the winding of common relay 1102. Relay 1102 is held operated and the group of trunks busy. Relay 1102 is slow 75 to release so that these holding circuits are closed before it releases. Ground for these holding circuits is also supplied by relays 1222 and 1221 to insure that the group remains busy as long as the equipment is in use 80 in the extension of the call.

85 Relay 1223 closes a circuit from ground, over its inner upper front contact, outer upper back contact of relay 1222, winding of relay 1227 to battery. A circuit is also closed from ground over the inner upper front contact of relay 1223, inner upper back contact of relay 1228, lower front contact of relay 1227, winding of relay 1221 to battery. Thereupon a circuit is closed from battery, 90 through the winding of relay 1222, inner front contact of relay 1227, lower front contact of relay 1221, normal contact of brush 1212 to ground. With relay 1222 operated, the circuit of relay 1227 is extended over the 95 inner upper front contact of relay 1222, inner upper front contact of relay 1221, outer upper back contact of relay 1228, third front contact of relay 1224, 4th back contact of relay 1225 to the ring conductor. Relay 1227 100 responds to impulses from the sender, closing a circuit from battery, through the winding of magnet 1211, outer lower back contact of relay 1227, lower front contact of relay 1222, to ground at the outer lower front contact 105 of relay 1223. Relay 1222 is held operated over the inner lower back contact of relay 1227 to the operating ground for magnet 1211.

110 When the proper number of impulses have been transmitted relay 1227 is held operated, relay 1222 releases and a circuit is closed from battery, through the stepping magnet 1201 and its back contact, second front contact of relay 1224, third back contact of relay 1225, lower back contact of relay 1228, outer lower 115 back contact of relay 1222, off normal terminals of brush 1212 to ground. Magnet 1201 steps switch 1200 in search of an idle selector which is characterized by low resistance battery on the terminal served by brush 1203. 120 When such a selector has been found a circuit is completed from battery, for example on terminal 1230, brush 1208, first back contact of relay 1225 and its right winding, right front contact of relay 1224, brush 1202, terminal of group 1251, brush 1215, inner lower 125 back contact of relay 1222 to ground at the outer lower front contact of relay 1223. Relay 1225 operates in this circuit, and closes a holding circuit for itself from battery, 130

- through the winding of magnet 1201, second front contact of relay 1224, second front contact, left winding and first front contact of relay 1225, first front contact of relay 1224 to ground. The operation of relay 1225 opens the circuit of relay 1223 and that relay releases in turn releasing relays 1221 and 1227. With relay 1223 released a circuit is closed from battery, through the winding of magnet 1211, lower back contacts of relay 1227, lower back contact of relay 1223, back contact of magnet 1211, off normal terminals of brush 1212 to ground. Switch 1210 is stepped back to normal in this circuit to be ready to serve other selectors of the group to which it is common. The release of relay 1221 opens the holding circuit of relay 1102 and the interoffice trunks are made idle to third group selectors.
- 20 The row of terminals corresponding to terminal 1231 serves to give a busy signal to the calling subscriber and to release the selectors subsequent to the first group selector if no idle intermediate selector is found, the operation being substantially the same as for the second group selector. The row of terminals corresponding to terminal 1232 serves a similar purpose for incoming trunks of a sort not shown.
- 30 An intermediate selector might, in practice be employed between the incoming selector of Fig. 12 and a final selector. This selector would be controlled by the second numerical digit and might be substantially like the selector of Fig. 9. Such a selector has been omitted as unnecessary to a complete understanding of the invention.
- 40 The final selector of Figs. 13 and 14 is one which serves only individual lines and the equipment of Fig. 14 is common to a plurality of selectors. If the number dialed is that of an individual line so that selector 1300 is selected, the ground connected to conductor 1318 completes a circuit extending over the outer right back contact of relays 1312 and 1311, left winding of relay 1310, through the winding of relay 1408 to battery or to battery over the outer left back contacts of relays 1406 and 1408, inner right back contact of relay 1407, middle left back contact of relay 1406, normal contact of brush 1404, and resistance 1405. Relays 1408 and 1310 operate in this circuit. Relay 1310 locks in a circuit from battery through its right winding and 1st right contact to ground at the right front contact of relay 1408 and connects the selector with the common control circuit of Fig. 14. It also closes a circuit from battery through the winding of relay 1317, inner left contact of relay 1310 to ground over conductor 1318. Relay 1317 locks over its right contact and the left back contact of relay 1314 to conductor 1318. The operation of relay 1408 closes a circuit for relay 1409, over the inner left back contact of relay 1407 to ground at the right front contact of relay 1408. With relay 1409 operated, relay 1410 operates from ground at the back contact of relay 1406. With the relays 1408, 1409 and 1410 operated a circuit is completed from battery through the winding of relay 1407, over front contacts of these relays, normal contact of brush 1402 to ground. Relay 1407 transfers the circuit of relay 1409 to the inner right front contact of relay 1407, left front contact of relay 1410, 4th left front contact of relay 1310 to the ring conductor. Ground is connected to the tip conductor over the outer left front contact of relay 1407 and the 3rd left front contact of relay 1310, completing circuits to the sender. Relay 1409 responds to pulses from the sender and at each release closes a circuit for magnet 1401 extending over the outer right back contact of relay 1409, right front contact of relay 1407 to ground at the outer left front contact of relay 1408. The circuit of relay 1407 is opened as soon as switch 1400 steps off normal, but it is held operated during pulsing over the inner left front contact of relay 1408, inner right back contact of relay 1409, inner right front contact of relay 1407 to ground at the outer left front contact of relay 1408.
- 50 At the completion of the impulsing, relay 1407 releases, restoring relay 1409 to the control of relay 1408 and closing a circuit from battery through the winding and back contact of magnet 1301, inner right back contact of relay 1312, fourth right contact of relay 1310, inner left back contact of relay 1411, outer right back contact of relay 1407, off normal contacts of brush 1402 to ground. Switch 1300 is advanced to hunt for the group of trunks marked by brush 1404 of switch 1400. When this terminal is reached a circuit is closed from battery through the winding of relay 1411, second right contact of relay 1310, brush 1305, marked terminal, for example terminal 1319, terminal of brush 1404, middle back contact of relay 1406, inner right back contact of relay 1407 to ground at the outer left front contact of relay 1408. Relay 1411 in operating opens the above traced circuit for magnet 1301 and brings the switch 1300 to rest. Relay 1411 in operating also closes a circuit from battery through magnet 1401, outer right back contact of relay 1406, middle right front contact of relay 1411, back contact of magnet 1401, off normal contacts of brush 1402 to ground. Magnet 1401 restores switch 1400 to normal. A circuit previously existed for relay 1406 from battery through its left winding, inner right back contact, outer right back contact of relay 1407, off normal contacts of brush 1402 to ground. However, relay 1406 could not operate in this circuit since it was shunted by the circuit above traced for magnet 1301. When relay 1411 operates this shunt is

opened and relay 1406 closes its inner right front contact. A circuit now exists from battery through both windings of relay 1406, inner right front contact of relay 1406 to ground at the outer left front contact of relay 1408, but this circuit is shunted by the circuit over the off normal contact of brush 1402, since relay 1406 does not attract its other armatures sufficiently to open or close their contacts. When switch 1402 reaches normal this shunt circuit is opened and relay 1406 completely operates through its two windings. Relay 1407 reoperates in the previously traced circuit when brush 1402 reaches normal and relay 1411 releases. The operation of relay 1407 again connects relay 1409 to the ring conductor to respond to the units pulses. Switch 1400 is advanced to a position corresponding to the units digit in the same manner as it responded to the tens-digit. When relay 1407 releases at the completion of the impulses, magnet 1301 is operated in the circuit previously traced to advance switch 1300 in search of the terminal marked within the group selected. When this terminal is found a circuit is completed from battery, through the winding of relay 1411, second right contact of relay 1310, brush 1305, marked terminal, for example terminal 1320, brush 1403, outer left front contact of relay 1406, inner right back contact of relay 1407 to ground at the outer left front contact of relay 1408. Relay 1411 brings switch 1300 to rest in the manner previously described. The final selector now tests the subscriber's line to determine whether or not it is busy, this circuit extending from battery on terminal 1321 if the line is idle, brush 1304, left winding of relay 1312, third right contact of relay 1310, outer right front contact of relay 1410, outer right front contact of relay 1406, middle left front contact of relay 1411, back contact of magnet 1401, off normal terminals of brush 1402 to ground. Assuming that the line is idle, relay 1312 operates to complete the tip conductor and locks from ground on conductor 1318, through its right winding and inner right front contact, back contact and winding of magnet 1301 to battery. It also extends grounded conductor 1318 over its outer right front contact and brush 1304 to the cut-off relay of the subscriber's line to operate that relay and hold the line busy. The operation of relay 1406 opens the original energizing circuit of relay 1410, but a second circuit is extended to the back contact of relay 1411. At the completion of the units digit impulses, relay 1411 operated and opened the circuit of relay 1410. Since this relay is slow to release, the above described test circuit through relay 1312 was completed long enough to permit the operation and locking of relay 1312 before relay 1410 released, opening the energizing circuit of relay 1312. The operation of relay 1312 opens the circuit of relay 1408 and that relay releases to in turn release the remaining relays of the control circuit and restore switch 1400 to normal. The release of relay 1408 opens the holding circuit of relay 1310 and that relay also releases. A circuit is thereupon closed from ground through ringing machine 1315, right winding of relay 1314, right back contact of relay 1310, inner right back contact of relay 1314, inner left front contact of relay 1312, brush 1302, over the tip side of the subscriber's line, back over the ring side, brush 1303, middle right front contact of relay 1312, outer right back contact of relay 1314, resistance 1316 to battery. The subscriber's line is signaled over this circuit. A branch of the circuit extends over the outer left front contact of relay 1312, and condenser 1322 to connect ringing tone to the calling subscriber's line. Relay 1314 is so adjusted that it will not operate in series with the substation ringer, but does operate when the subscriber answers. It thereupon completes the ring conductor and closes a shunt around condenser 1322 to improve talking conditions. It also connects the windings of relay 1323 to the called subscriber's line to supply talking current thereto. The operation of relay 1323 connects battery over the front contact of relay 1317, right winding of relay 1313, 1st inner left back contact of relay 1310 to the tip conductor. Had the called line been busy, ground instead of battery would have been connected to terminal 1321 and relay 1312 would not have operated. When relay 1410 released a circuit would have been closed from battery through resistance 1412, inner right front contact of relay 1411, outer left back contact of relay 1410, 4th front contact of relay 1310 to the ring conductor operating relay 713. No ground is connected to the tip conductor at this time since relay 1406 is operated and relay 1407 is not operated, therefore relay 713 is operated alone resulting in a busy signal to the calling subscriber and the release of the selectors as previously described. Figs. 16 and 17 show a final selector having access to private branch exchanges. For that purpose it is provided with two auxiliary switches, 1700 which responds to the tens impulses, and 1710 which responds to units impulses. The seizure of the final selector causes the operation of relays 1610 and 1720. Relay 1720 operates relay 1721. Relay 1721 operates relay 1722 and relay 1722 operates relay 1724. The operation of relay 1724 connects relay 1721 to the ring conductor to respond to dial pulses. The response of relay 1721 to dial pulses closes a circuit from battery through the winding of magnet 1701, outer left back contact of relay 1725, inner right back contact of relay 1721, left front contact of relay 1724, outer left front contact of relay 1720 to ground. Magnet 1701

advances switch 1700. The energizing circuit of relay 1724 is opened at brush 1703 but that relay is held over the back contact of relay 1721 during pulsing.

- 5 When relay 1724 releases at the end of the series, a circuit is closed from battery through the winding of magnet 1711, back contacts of relays 1725, 1726, magnet 1711 and relay 1724, front contact of relay 1720, off normal contacts of brush 1703 to ground. Switch 1710 is advanced in search of the terminal marked by brush 1704. When this terminal is found a circuit is closed from battery through the winding of relay 1726, brush 1714 and 15 the marked terminal, brush 1704, back contact of relay 1724, and thence as previously traced to ground over brush 1703. The operation of relay 1726 brings switch 1710 to rest. The operation of relay 1726 also closes a 20 circuit from battery, through the winding of relay 1725, inner right front contact of relay 1726, inner left front contact of relay 1720 to ground. Relay 1725 locks to ground at the front contact of relay 1720 independent 25 of relay 1726.

The reception of the units impulses causes the operation of magnet 1711 over the outer left front contact of relay 1725 and the back contact of relay 1721, switch 1710 being advanced to a terminal within the marked 30 group. The advance of switch 1710 causes the release of relay 1726. When relay 1724 releases at the end of the units impulses, a circuit is closed from battery, through the winding of magnet 1601 of the final selector, over its back contact, inner left back contact of relay 1611, 3rd right contact of relay 1610, inner left back contact of relay 1723, inner left front contact of relay 1725, back 35 contact of relay 1726, back contact of magnet 1711, back contact of relay 1724, front contact of relay 1720 to ground over the off normal terminals of brush 1703.

When brush 1605 encounters the terminal marked, for example terminal 1621, a circuit will be completed from battery through the winding of relay 1723, brush 1712 and its corresponding contact, terminal 1621, brush 1605 to ground at the outer right contact of 40 relay 1610. Relay 1723 locks over its inner right contact to ground at the middle left contact of relay 1720. If this contact represents the first of a group of trunks leading to a private branch exchange, relay 1727 will be connected to the corresponding terminal in the arc served by brush 1713 and a circuit will be completed through the winding of relay 1727, brush 1713, front contact of relay 1723, contact and brush 1606 to ground on the front contact of relay 1610. With relay 45 1727 operated a circuit is closed from battery through winding of magnet 1601 and its back contact, inner left back contact of relay 1611, 3rd right contact of relay 1610, left front contact of relay 1727, inner left front contact of

relay 1725, back contact of relay 1726, back contact of magnet 1711, inner left back contact of relay 1724, outer right front contact of relay 1720, off normal terminals of brush 1703 to ground. Magnet 1601 advances switch 1600 in search of an idle trunk within the group. Relay 1727 is held operated since the terminals corresponding to these trunks are strapped together. When an idle trunk is found, relay 1611 operates in a circuit from 70 battery on the contact engaged by brush 1604, left winding of relay 1611, second right contact of relay 1610, inner left front contacts of relays 1722, 1723 and 1725, and thence to ground as traced for the circuit of relay 1727. 75 Relay 1611 locks in a circuit from battery through the winding of magnet 1601, inner left front contact and right winding of relay 1611, to ground over conductor 1620. The operation of relay 1611 releases relay 1720 80 and in turn relay 1610 and the common apparatus of Fig. 17. With relay 1610 released a circuit is closed from battery through right winding of relay 1615, outer right back contact of relay 1612, left winding of relay 1614, 85 left back contacts of relays 1613 and 1614, inner left back contact of relay 1610 to the ring conductor, and from ground through the left winding of relay 1615, right winding of relay 1614, right normal contact of relay 90 1613, middle left back contact of relay 1610 to the tip conductor. With relay 1611 operated ringing takes place in a manner substantially as described in connection with Fig. 13 and the response of the called subscriber operates relay 1613 to reverse the connection of battery and ground to the tip and 95 ring conductors. 100

Returning to the sender, following the sending of the last numerical digit, switch 800 will have reached its normal position. At this time a circuit is closed from battery through the winding and normal contact of relay 408, 2nd front contact of relay 404, 105 normal contact of brush 803 to ground at the 4th front contact of relay 404. Relay 408 locks over its inner left contact to ground at the 2nd front contact of relay 400. The operation of relay 408 opens the circuit of relay 400 and that relay releases after an 110 interval due to its slow releasing character, at which time relay 408 also releases. The release of relay 400 opens the circuit of relay 203, and disassociates the sender from the 1st group selector. The release of relay 203 115 also extends the talking conductors from the calling line through to the called line. The release of relay 400 also releases any other relays such as relay 710 which may be locked to its front contacts. It also supplies re- 120 storing circuits for the register switches 510, 520, 530 and 540, returning them to normal. The release of relay 203 closes a bridge across the outgoing side of the trunk, extending 125 from the tip conductor, normal contact of 130

relay 208, winding of relay 211, inner front contact of relay 200, lower winding of relay 216, to the ring conductor. When relay 1613 or 1323 in the final selector operates reversing the connection of battery to the interoffice trunk, relay 216, which is electrically polarized by an obvious circuit through its upper winding, operates and opens the holding circuit for relay 205. Relay 205 releases slowly due to its character and when fully released completes a circuit for register 131 extending from battery through the register, outer right contact of relay 103, through the line finder 110, link 100, selector finder 120, 3rd back contact of relay 205, upper contact of relay 216, to ground at the 4th front contact of relay 201. When the calling party hangs up, line relay 200 is released and a circuit is closed momentarily to ground over the outer back contact of relay 200, 1st front contact of relay 201 to the winding of relay 208. Relay 208 again operates relay 205 and closes a temporary holding circuit for relay 211 from battery over the outer right contact of relay 208, winding of relay 211 to ground over the inner back contact of relay 200. Relay 201 is slow to release and so too is relay 208. With these two relays completely released, relay 211 is connected between ground and the tip of the outgoing trunk over the normal contact of relay 208 to provide for holding the circuit busy in cases where the outgoing trunk extended to an operator's position. With relays 201 and 211 both deenergized cut-off relay 103 and link relay 123 are released. The release of relay 205 following the release of relay 201, releases relay 210 and disconnects ground from conductor 938. The removal of ground from conductor 938 releases relays 927 and 1100. The release of relay 1100 opens the circuit of relay 1103, but this relay being slow to release remains operated long enough to connect battery through resistance 1106 over its inner front contact and the inner left back contact of relay 1100 to the tip conductor, and over its outer front contact and the outer left back contact of relay 1100 to the ring conductor of the interoffice trunk. The currents flowing through the two windings of relay 1226 therefore aid one another, operating relay 1226 and releasing relays 1224 and 1225. The release of these relays removes the holding ground from the final selector and from the subscriber's line, thus completely freeing the connection.

Routine testing of control circuit

Test circuits are provided for performing routine tests on the control equipment of all selectors, but only that for testing second group selectors has been shown. Testing is started by operating start key 1020 and continues until the key is opened. The test equipment has access to the control circuits by means of a rotary switch which has no normal position and testing begins with the circuit on which the switch happens to be standing. If that control circuit is idle, battery will be connected to conductor 931 through the winding of relay 922, and from the normal contact of brush 912. If battery is present, a circuit will be completed as soon as key 1020 is operated from conductor 931 over terminal 1021, brush 1009, right contact of key 1020, 4th right back contact of relay 1023, outer left back contact of relay 1024, winding of relay 1025, inner right back contact of relay 1026, right winding of relay 1027, brush 1002, terminal 1022, conductor 934, normal terminal of brush 913, to ground at the 3rd left back contact of relay 922. Relays 1025 and 1027 operate in this circuit. If the control circuit is busy the above traced circuit cannot be closed until the circuit becomes free. In the meantime ground is connected to conductor 1030 by an interrupter (not shown) and a circuit is completed over left back contact of relay 1029, middle contact of key 1020, 3rd right back contact of relay 1023, back contact of relay 1031, right winding of relay 1029 to battery. This relay operates substituting a permanent ground over its right contact and through its right winding for the interrupted ground over conductor 1030. If the start circuit has not closed by the time that the next closure of ground to conductor 1030 occurs a circuit will be extended over the left front contact of relay 1029, left normal contact and winding of relay 1024 to battery. Relay 1024 locks over its left alternate contact to ground on key 1032. It connects ground over its right front contact and brush 1007 to lamp 1033, individual to the particular control circuit, indicating that the control circuit is falsely busy. This circuit also operates an alarm in series with the lamp. Relay 1024 also closes a circuit for magnet 1001 of the rotary switch to hold it operated and prevent advancing the brushes until the fault has been recorded and the circuit released by operating key 1032. The energizing circuit of relay 1029 may be closed during a test, but the operation of relay 1031 as will be described hereinafter, repeatedly interrupts the locking circuit of relay 1029 and prevents its maintenance long enough to permit the operation of relay 1024.

Assuming that relays 1025 and 1027 are operated, the test circuits are completed extending between the control circuit and the test relays of the test circuit. Relay 922 operates in the circuit with relays 1025 and 1027, in turn operating relays 923, 925 and 924, the operation of relay 924 connecting relay 923 to conductor 935 which is a branch of the circuit extended to the ring conductor in service. Relay 923 is held operated over ter-

5 minal 1038, brush 1004, 4th back contact of relay 1023, inner right contact of relay 1025, left normal contact of relay 1036, winding of relay 1039, to ground at the left normal contact of relay 1040. Relay 1039 also operates in this circuit. In addition a circuit is closed from battery through the winding of relay 1035, right normal contact of relay 1036, outer right contact of relay 1025, 3rd left 10 back contact of relay 1023, brush 1003, terminal 1037, conductor 933 to ground at the left back contact of relay 921, to test for this ground. With relays 1035 and 1039 both operated, relay 1036 is operated over their 15 front contacts. Relay 1036 locks over its inner left front contact to the strapped terminals of brush 1015 and ground. The operation of relay 1036 transfers the circuit of relay 923 from the winding of relay 1039 to brush 1013, and the grounded circuit from relay 1035 to the normal terminal of brush 1013 thus maintaining the energization of relay 923. Relays 1035 and 1039 are therefore deenergized to close a circuit from battery 20 through the winding of relay 1031, back contact of magnet 1011, outer right back contact of relay 1024, brush 1014 and its four strapped terminals, inner right front contact of relay 1036, to ground at the left back 25 contact of relay 1039. Relay 1031 closes an obvious circuit for magnet 1011. Magnet 1011 in operating opens the circuit of relay 1031 which releases after an interval and in turn releases magnet 1011. Switch 1010 is 30 advanced in this manner to its 5th terminals at which time the circuit of relay 1031 is opened. When brush 1013 left its normal terminal, it opened the circuit of relay 923, and when it reached its 5th terminal it re- 35 closed the circuit thus permitting a single release of relay 923 which operates magnet 911 once to advance switch 910 to its 1st off normal position. When relay 924 releases following this impulse, a circuit is closed 40 from ground over the 3rd left contact of relay 922, middle left back contact of relay 924, brush 912 and its 1st off normal terminal to conductor 936, terminal 1041, brush 1005, middle left contact of relay 1025, 1st 45 right back contact of relay 1023, 5th terminal of brush 1014, and thence to the winding of relay 1031, resulting in the advance of switch 1010 to its 6th terminals. When switch 1010 leaves its 5th terminals, relay 1036 releases. 50 The release of relay 924 also closes a circuit from ground over the terminals of brush 915, outer left back contact of relay 924, middle left back contact of relay 926, conductor 937, terminal 1042, brush 1006, outer left contact 55 of relay 1025, 2nd right back contact of relay 1023, 6th terminal of brush 1014 to the winding of relay 1031, advancing switch 1010 to its 7th terminal. With relay 1036 released, relay 1035 is again connected to conductor 60 65 933, and relay 1039 to conductor 935.

When relay 1027 operated, as described at the beginning of this test, it connected ground over its inner left contact to the winding of relay 1025, to hold that relay operated. It also closes a holding circuit for itself from battery through its left winding and outer right contact, right normal contact of relay 1026, inner right front contact of relay 1027 to ground. In addition it closed a circuit from ground over its inner left front contact, inner right back contact of relay 1026, right winding of relay 1027, brush 1002, terminal 1022, conductor 934, normal contact of brush 913, 4th left front contact of relay 922, inner back contact of relay 929, right winding of relay 921 to battery. Relay 921 closes its outer front contact, completing a circuit through both windings to ground at the right contact of relay 922, which circuit is ineffective because of the shunt over the original operating circuit. When test switch 1010 stepped off normal, a circuit was closed from battery through the winding of relay 1026, off normal contacts of brush 1012 to ground. Relay 1026 opens the energizing circuit of relay 921, permitting that relay to completely energize. It also extends its operating ground over its right front contact to the outer right contact and left winding of relay 1027 to hold that relay operated. If relay 921 has 95 operated correctly the connection of relays 1035 and 1039 to conductors 933 and 935 respectively is ineffective and a circuit is completed for relay 1031 over the 7th terminal of brush 1014 and back contact of relays 1035 100 and 1039 to ground advancing switch 1010 to position 8.

In this position a circuit is closed from battery through the winding of relay 926, inner front contact of relay 921, 4th front contact of relay 922, terminal 1043 and brush 1008, 2nd left contact of relay 1023, inner left front contact of relay 1025, right winding of relay 1040, 8th terminal of brush 1015 to ground. Relay 926 operates, but relay 1040 110 is marginal and cannot operate at this time. Relay 926 closes a circuit from battery through resistance 932, outer left front contact of relay 926, conductor 935, and thence to the winding of relay 1039 and ground at the back contact of relay 1040. Relay 1039 operates closing a circuit from ground over its right front contact, 8th terminal of brush 1014, and thence to relay 1031 to advance switch 1010 to position 9. The operation of 115 relay 926 opens the circuit of relay 925, and when that relay releases completely it closes a shunt through resistance 940 around the winding of relay 926, permitting relay 1040 to operate in the previously traced circuit. Relay 1040 locks over its inner left front contact to ground at the inner left contact of relay 1026. Relay 1040 connects ground over its right contact to the 9th terminal of brush 1014 to advance switch 1010 to position 10. 120 125 130

In position 10 the above traced circuit for relay 926 is opened and that relay releases, in turn releasing relay 1039. With relays 1039 and 1035 both released switch 1010 is advanced to position 11. In position 11 a circuit is closed from battery over the left back contact of relay 1036, brush 1013 and its 11th terminal; left front contact of relay 1040, winding of relay 1039, left normal contact of relay 1036, thence as previously traced to conductor 935, back contact of relay 926, back contact of relay 925 to ground. The operation of relay 1039 in this circuit advances switch 1010 to position 1.

With switch 1010 in position 1 relay 1027 is released. When relay 1027 operated it closed a circuit from battery through the winding of magnet 1001 to ground at the outer left contact of relay 1027. With relay 1027 released, this circuit is opened and magnet 1001 releases, advancing switch 1010 to the next control circuit. If the control circuit fails to operate correctly at any point, switch 1010 will not be advanced and relay 1029 will be operated to in turn operate relay 1024 and light the corresponding lamp in the manner described for a prolonged busy condition. When all of the control circuits have been tested in succession, brushes 1009 and 1007 engage terminals 1050 and 1051. Relay 1026 is slow to release and therefore will not have retracted its armatures by the time brush 1007 engages terminal 1051. Therefore a circuit will be closed from battery through the winding of relay 1023 and its 1st back contact, outer left front contact of relay 1026, inner right back contact of relay 1024, brush 1007, terminal 1051 to ground. Relay 1023 locks over its left front contact to the left contact of the start key 1020. With relay 1023 operated a circuit is closed from battery through resistance 1045, terminal 1050, brush 1009, right contact of start key 1020, outer right front contact of relay 1023, back contact of magnet 1001, winding of relay 1044 to ground. Relay 1044 energizes the magnet 1001 which opens its contact thereby releasing relay 1044 and subsequently magnet 1001 to advance switch 1000 to the next control circuit. The test circuit therefore continues to test the busy or idle condition of the control circuits in order, and the duration of the busy condition until the start key 1020 is opened. Keys 1052 and 55 1053 control relays 1044 and 1031 respectively and thus permit the setting of switch 1000 or switch 1010 on a particular set of terminals if desired.

Line number indicator

In order to prevent the tying up of an excessive amount of apparatus due to false grounding of a subscriber's line, the circuit shown in Fig. 15 is provided to detect such 65 false grounds and to indicate on which line

it occurs. A false ground will cause the operation of line relay 102, the selection of an idle link, and of a first group selector in the manner described. Since this is a false ground no dialing will follow this operation and consequently relay 405 will not be operated. An interrupter (not shown) periodically connects ground to conductor 417. This completes a circuit over back contact of relay 409, outer right back contact of relay 405, left winding of relay 409 to battery. Relay 409 closes its inner contact and when ground is removed from conductor 417, closes its outer contact, and remains operated in a circuit from battery through its left winding, outer right back contact of relay 405, right winding and inner right contact of relay 409, conductor 418, outer and middle left contacts of relay 700 to ground. The next closure of ground to conductor 417 completes an obvious circuit through the left winding of relay 402. Relay 402 locks in a circuit from battery through its right winding, 3rd back contact of relay 404, normal contact of brush 803, second back contact of relay 404, outer right front contact of relay 402 to ground through key 403. The operation of relay 402 closes a circuit from battery through the winding of relay 207, 12th front contact of relay 203, inner right front contact of relay 402 to ground. Relay 207 operates and closes a circuit from ground over its 2nd front contact, 1st back contact of relay 205, to conductor 212. It also closes a circuit from battery through resistance 240, 3rd front contact of relay 207, 3rd back contact of relay 205, to terminal 128 of the selector finder, whence it is extended through the link circuit and the line finder to terminal 141 and thence to conductor 129. Twenty switches, of which switch 1535 is one, are provided, each switch being of the type of the selector switches having no normal position and having access to 100 sets of terminals. The terminal corresponding to terminal 141 of each subscriber's line is connected to a terminal in one of these 20 switches. The location of this terminal bears a direct relationship to the line number. That is, the first brush of the first switch will have access to lines 0 to 99, the first switch will have access to lines 4 to 499, and the entire group has access to lines 0 to 9999. Magnets 1501 and 1520 represent the operating magnets for the first and the twentieth of the switches. Two other switches are provided, one controlled by magnet 1521 to which brushes 1540 and 1541 belong, and one operated by magnet 1522 to which brushes 1542, 1543 and 1544 belong. 115

The connection of ground to conductor 125 212 completes a circuit over key 1530, winding of relay 1531 to battery. The operation of relay 1531 in this circuit closes a circuit from battery through the winding of relay 1533, back contact of relay 1536, left front 130

contact of relay 1531, back contact of magnet 1521, back contact of magnet 1501, and thence serially over the back contacts of the magnets of the other switches to ground at the 5 back contact of magnet 1520. The operation of relay 1533 closes circuits in parallel for magnets 1501 to 1520 and also for magnet 1521. The operation of the magnets opens the circuit of relay 1533 and that relay releases in turn releasing the magnets and the 10 switches are therefore stepped along until contact 1532 in which conductor 129 terminates is reached. The operation of relay 1531 prepares a circuit from ground over 15 its right contact in parallel through the windings of relays 1534, 1537, 1538, 1539 and 1550 to the brushes of switch 1535 and through similar sets of relays to the brushes of the other switches. When terminal 1532 20 is reached the circuit of the relay connected to the corresponding brush, in this case relay 1534, will be completed and that relay operated. The operation of any one of these relays completes a circuit from ground over 25 the front contact of that relay through the winding of relay 1536 to battery. Relay 1536 in operating permanently opens the circuit of relay 1533 and stops the switches. With relay 1536 operated a circuit is closed 30 from battery through the winding of magnet 1522 and its back contact, front contact of relay 1536 to the winding of relay 1545 and ground. The terminals over which brush 1544 moves are connected to the back 35 contacts of relays 1534, 1537, 1538, 1539 and 1550. There is a terminal for each brush of each switch and since each brush has access to 100 lines, each terminal identifies a particular group of 100 lines. If the brush 1524 40 is engaging a terminal corresponding to an unoperated relay, ground will be connected to the terminal, over the back contact of the corresponding relay, and relay 1545 will be prevented from operating while magnet 1522 45 will be operated to advance brush 1544 to the next terminal. When a terminal is found from which ground is disconnected due to the operation of the corresponding relay, relay 1545 operates but magnet 1522 cannot operate in series with relay 1545. The operation 50 of relay 1545 provides ground for lighting the identifying lamps. Since brushes 1540 and 1541 were moved simultaneously with brush 1535, they will engage terminals corresponding 55 to the position of the line in the particular hundred to which it belongs and therefore indicate the tens and units digits of the calling line number. The position of brush 1544 identifies both the switch and the 60 brush which engaged terminal 1532, corresponding to the calling line and hence the group of one hundred lines to which it belongs. Therefore the terminals of brushes 1542 and 1543 which form part of the same 65 switch as brush 1544 identify the thousands

and hundreds digits of the line number. The circuits of the lamps extend from battery through the winding of relay 1546, through the four lamps to be lighted and the terminals and brushes leading thereto to ground through the front contact of relay 1545. The operation of relay 1546 lights lamp 1547 to call attention to the fact that a permanent ground exists and may also be used to sound an alarm if desired. 70

What is claimed is:

1. In a telephone exchange system, a group of selector switches each having a bank of terminals divided into groups, an auxiliary switch common thereto, means for transmitting impulses for positioning said auxiliary switch to mark a group of terminals in any one of said banks, and means effective only after said group has been marked for causing one of said selector switches to hunt for an idle terminal in the group marked. 80

2. In a telephone exchange system, a group of selector switches each having a bank of terminals divided into groups, an auxiliary switch common thereto, means effective if said auxiliary switch is normal for selecting one of said selector switches, means for rendering said auxiliary switch individual to said selected selector, means for transmitting impulses for positioning said auxiliary switch to mark a group of terminals in the bank of said selector, and means effective only after said group has been marked for causing said selector switch to hunt for an idle terminal in the group marked. 90

3. In a telephone exchange system, calling lines, groups of trunk circuits, a sender common to the trunk circuits of each group, link circuits, each link circuit being adapted to connect a calling line with a trunk circuit in a particular group, a switch for selecting an idle link circuit, and means operated by the initiation of a call for causing said switch to select an idle link circuit which has access to a group of trunk circuits associable with an idle sender. 100

4. In a telephone exchange system, a calling line, a group of trunk circuits, a sender common to the trunk circuits of the group, means for connecting said calling line with an idle trunk circuit, and relay means operative upon the seizure of any trunk circuit to connect said trunk circuit with said sender. 115

5. In a telephone exchange system, a calling line, a called line, a first group selector, other group selectors and a final selector for extending a connection from said calling line to said called line, groups of trunks accessible to each of said group selectors, a busy signaling device at said first group selector, and means operative when any group selector finds all the trunks of a group, in which it has been directed to hunt, busy, for causing said signaling device to transmit a busy signal to said calling line and for causing the 120 125 130

release of all operated selectors beyond said first group selector.

6. In a telephone exchange system, a calling line, a called line, a first group selector, 5 other group selectors and a final selector for extending a connection from said calling line to said called line, groups of trunks accessible to each of said group selectors, a busy signaling device at said first group selector, and 10 means operative when any group selector has twice reached a particular position for causing said signaling device to transmit a busy signal to said calling line and for causing the release of all operated selectors beyond 15 said first group selector.

7. In a telephone exchange system, a calling line, a called line, a first group selector, other group selectors and a final selector for extending a connection from said calling line 20 to said called line, a busy signaling device at said first group selector, and means operative when said final selector has been directed to the terminals of said called line and found said line busy for causing said signaling device 25 vice to transmit a busy signal to said calling line and for causing the release of all operated selectors beyond said first group selector.

8. In a telephone exchange system, a calling line terminating in one office, a second 30 office, a group of two-wire trunks extending between said offices, selector switches for extending said calling line over an idle one of said trunks to said second office, incoming selectors at said second office in which said 35 trunks terminate, control apparatus at said second office common to said incoming selectors, and means at the outgoing ends of said trunks operable over said trunks for rendering all of the trunks of the group busy when 40 said common control apparatus is engaged for use with any one of said incoming selectors.

9. In a telephone system, a two-wire inter-office trunk, means to establish a connection 45 from a calling subscriber's line to said trunk, means to complete said connection from said trunk to a called subscriber's line, a differential relay having its windings connected in the two wires of said trunk at the end nearest the called subscriber's line, means under 50 the control of said relay to maintain said connection from said trunk to the called subscriber's line, and means responsive only after said connection has been opened at both 55 the calling and called subscribers' lines to operate said relay to release the connection to the called line.

10. In a telephone system, a two-wire inter-office trunk, means to establish a connection 60 from a calling subscriber's line to said trunk, a differential relay having its windings connected in the two wires of said trunk at the distant end, means to establish a connection from the distant end of said trunk to a 65 called subscriber's line without operating

said relay comprising means under the control of impulses transmitted over a circuit extending over the two wires of said trunk in series, and means to initiate the sending out of the successive sets of impulses by means of 70 separate circuits extending in opposite directions over the two wires of said trunk, means controlled by said relay to maintain said connection from said trunk to said called subscriber's line, and means responsive to the 75 opening of the connection at both the calling and called lines to establish separate circuits extending in the same direction over the two wires of said trunk to operate said relay and release said trunk from said called subscriber's line.

11. In a telephone exchange system, a plurality of calling lines, switching mechanism for extending a connection from any one of said lines, a sender for controlling said 80 switching mechanism, means associated with each calling line for controlling said sender, and automatic switching means operated after a predetermined interval following the initiation of a call by a calling line if the 85 calling line has exercised no control over said sender for selecting the particular calling line and for identifying it.

12. In a telephone exchange system, a calling line, switching mechanism operable from said line for extending a connection therefrom, and automatic switching means operated after a predetermined interval if an unstandard condition exists on said line for 90 selecting said line and for identifying it. 95

13. In a telephone exchange system, a group of switches each having a bank of terminals divided into groups, an auxiliary switch common thereto, means for transmitting impulses for positioning said auxiliary switch to mark the sets of terminals of a particular group in any one of said banks, other means to mark the idle sets of terminals in said banks, means for operating one of said selector switches, and means for arresting said switch when it engages a set of said terminals simultaneously marked by said auxiliary switch and by said other means. 105

14. In a telephone exchange system, a group of switches each having a bank of terminals divided into groups, and having no normal position, an auxiliary switch common thereto, means for transmitting impulses for positioning said auxiliary switch to 115 mark the sets of terminals of a particular group in any one of said banks, other means to mark the idle sets of terminals in said banks, means effective after the group has been marked by said auxiliary switch for operating one of said selector switches, and means for arresting said switch when it engages a set of said terminals simultaneously marked by said auxiliary switch and by 120 said other means. 125

15. In a telephone exchange system, calling lines, groups of trunk circuits, a sender common to the trunk circuits of each group, link circuits, each link circuit being adapted to connect a calling line with a trunk circuit in a particular group, a switch for selecting an idle link circuit, and means operated by the initiation of a call for causing said switch to select a link circuit which has access to a group of trunk circuits, the sender common to which is idle. 70
16. In a telephone exchange system, a calling line, a group of trunk circuits, a sender common to the trunk circuits of a group, means for connecting said calling line with an idle trunk circuit, and relay means individual to each trunk operative upon the seizure of the corresponding trunk circuit to connect said trunk circuit with said sender. 75
17. In a telephone exchange system, a first selector, other selectors, a sender for controlling said selectors, a sending switch in said sender, means to repeatedly position said switch in accordance with successive elements of a routing designation, means effective in the first set position of said switch to mark a setting for said first selector, and means effective during subsequent operations of said switch to transmit impulses to said other selectors. 80
18. In a telephone system, a calling line, a selector switch having no normal position for extending said calling line, means under the control of the calling line to mark a position of said switch, means to operate said switch to find said marked position, and means operative when said switch has twice reached a particular position to arrest said switch and to cause the transmission of a busy signal to said calling line. 85
19. In a telephone system, a calling line, a selector switch having no normal position for extending said calling line, means under the control of the calling line to mark a position of said switch, means to operate said switch to find said marked position, means operative when said switch has twice reached a particular position to arrest said switch and to cause the transmission of a busy signal to said calling line, and means to prevent the giving of said busy signal if said marked terminal is one of a particular group. 90
20. In a telephone exchange system, groups of selector switches, control circuits each individual to a group of selector switches, means in said control circuits for determining the position to be assumed by said selector switches, a testing circuit, means for progressively associating said testing circuit with said control circuits, means responsive to the idle condition of a control circuit to initiate a test of said control circuit, and means in said testing circuit for identifying a control circuit found to be in unstandard condition and for operating an alarm. 95
21. In a telephone exchange system, a plurality of control circuits, a testing circuit, means for progressively associating said testing circuit with said control circuits, means in said testing circuit to make a complete test of each control circuit by causing it to pass through a cycle of operations, other means in said testing circuit to test only the busy or idle condition of each control circuit and to operate an alarm if either condition is unstandard, and means automatically responsive following the complete testing of the last control circuit to render said other testing means effective. 100
22. In a telephone exchange system, a plurality of calling lines, switching mechanism for extending a connection from any one of said lines, a sender for controlling said switching mechanism, means associated with each calling line for controlling said sender, automatic switching means operated after a predetermined interval following the initiation of a call by a calling line if the calling line has exercised no control over said sender for selecting the particular calling line, and means controlled by said selecting means for displaying the number of said line. 105
